Filed Apr. 15, 1971, Ser. No. 134,541

Term of patent 14 years

Int. Cl. D4—02

U.S. Cl. D4—20

FIG. 1 is a top plan view of a cosmetic container embodying my new design;

FIG. 2 is a side elevational view thereof;

FIG. 3 is a perspective view thereof with the cover removed;

FIG. 4 is a perspective view of the cover of the cosmetic container with applicator brush attached;

FIG. 5 is a top plan view of the cover of FIG. 4;

FIG. 6 is a side elevational view of the cover of FIG. 4;

FIG. 7 is a side elevational view of a cover with applicator pad attached; and

FIG. 8 is a perspective view of the cover of FIG. 7.

The dominant features of my new design reside in the configuration of the cosmetic container and the cover therefor.

I claim:

The ornamental design for a cosmetic container, as shown and described.
